UNITED STATES PATENT OFFICE.

GEORGE H. COLLEY, OF JACKSON, MICHIGAN, ASSIGNOR TO THE WEEKS
COLLEY MANUFACTURING COMPANY, OF SAME PLACE.

SEWING-MACHINE.

SPECIFICATION forming part of Letters Patent No. 549,185, dated November 5, 1895.

Application filed December 18, 1894. Serial No. 532,165. (No model.)

To all whom it may concern:

Be it known that I, GEORGE H. COLLEY, a citizen of the United States, residing at Jackson, in the county of Jackson and State of Michigan, have invented certain new and useful Improvements in Sewing-Machines; and I do hereby declare the following to be a full, clear, and exact description of the invention, such as will enable others skilled in the art to which it appertains to make and use the same.

This invention relates to improvements in sewing-machines, but more particularly to such machines as employ an overseaming or zigzag stitch.

Heretofore it has been customary in the manufacture of corsets and the like to close by hand the open ends of the binding-strips used on such articles. This consumes considerable time, thereby involving extra expense, which it is always desirable to reduce to a minimum, and which is an important matter to be taken into consideration in a manufactured article, and, moreover, such hand-work is usually uneven in finish and the work necessarily unsatisfactory.

The primary object of my invention is to provide means attached to a sewing-machine whereby the ends of such binding-strips may be readily and effectually closed; to provide means for giving a step-by-step movement to the object; to provide means for feeding the object in either direction, so that one row of stitches may be made to cross the preceding row to more effectually close the ends of the strips; to provide means whereby the step-by-step mechanism may be automatically shifted to change the direction of the feed; to provide a clamp which will rigidly hold and align the object so as to be properly and positively fed; to provide a thread-tension-releasing device operated simultaneously with the releasing of the clamp, and to provide means for retaining the clamp in a raised position.

A further object is to provide simple, effective and durable mechanism which may be applied to various designs of machines and which may be adjusted to different requirements.

With these and other objects in view the

invention consists in the construction and combination of the several parts, as will be more fully hereinafter described, and then particularly pointed out in the claims at the end of the description.

Referring to the accompanying drawings, forming a part of this specification, Figure 1 is a general perspective view of my invention as applied to a Singer overseaming sewing-machine. Fig. 2 is a front end elevation with the overhanging arm removed, illustrating the relative position of the needle-bar and tension-releasing device to the other parts of the invention. Fig. 3 is a transverse section on the line III III of Fig. 4. Fig. 4 is a vertical longitudinal section through the clamp and feed-operating mechanism with a portion of the machine broken away. Fig. 5 is a plan view of the forward end of the clamp. Fig. 6 is an inverted plan of the top plate of the clamp. Fig. 7 is a plan of a portion of the foot-plate of the clamp. Fig. 8 is a section on the line VIII VIII of Fig. 3, illustrating the means for yieldingly retaining the pawl in different positions. Fig. 9 is a front elevation of a modified form of mechanism for giving a step-by-step movement to the rack-bar. Fig. 10 is a plan view of the rack-bar, and Fig. 11 is a transverse section of the rack-bar taken on the line 11 11 of Fig. 10.

In the drawings, A may designate a work-plate or bed, B the overhanging arm, C the head of the arm, D the needle-bar, having a reciprocating and vertical movement and carrying the needle d d', the link connected to a cam-actuated lever d², E the driving-wheel secured to the driving-shaft which operates the needle-bar, and F the vertical shaft for operating the shuttle mechanism G through the pitman g, all of which may be of any suitable construction and operated in the usual and well-known manner.

The bed A has a frame H, arranged upon the upper surface thereof, provided with a groove in which a rack-bar h is adapted to slide back and forth, as will be more fully hereinafter described.

At h' is a plate removably secured by screws or otherwise to the upper surface of the rack-bar and having its inner end forming one

side of a dovetailed recess in which is arranged the rear end or shank of the foot-plate *i* of the clamp *I*, so that by loosening or removing the screws which secure the plate *h*¹ to the rack-bar, and thus loosening the clamp, the latter may be adjusted lengthwise of the machine. This clamp has the top plate *i*², which is secured by the spring or springs *i*³ to the foot-plate-supporting arm *i*, the foot-plate serving to support the material and to align the same. The said foot-plate-supporting arm extends to the rack-bar parallel with but underneath the spring which supports the top plate, being secured to said rack-bar as described, said arm being offset at *i*⁴, so that its forward end or the foot-plate secured to said end may rest upon the bed of the machine. The foot-plate is provided with an L-shaped end *i*⁵ and an upwardly-extending lip *i*⁶, which passes through an elongated slot *i*⁷ of the top plate *i*² and serves to align the material when placed between said top plate and foot-plate. This top plate has a depending tooth-edged bar or rib *i*⁸ on the under side thereof which rigidly holds the material to the foot-plate, the elongated slot *i*⁷ of said plate being of sufficient length and width to permit proper movement of the clamp and the needle *d*, which passes through said slot. The rack-bar *h*, before referred to, is provided with teeth which are in mesh with a segmental or other form of gear *j*, secured to the end of shaft or stud *j*², which is journaled transversely of the frame *H*, the said gear or stud, as the case may be, having a handle *j*³ for moving the rack in either direction independently of any mechanism. On the stud *j*², between the sides *j*⁴ *j*⁵ of the frame *H*, are secured a pair of ratchet-wheels *k* *k*', having oppositely-arranged teeth which are adapted to be engaged by the oppositely-acting teeth *l* *l*' of the pawl *L*. The pawl is pivoted to rocking arm *l*² by a screw or bolt *l*³ and is held so as to cause either of the teeth of said pawl to engage their respective ratchet-wheels by a spring-pressed pin *l*⁴, (shown in Fig. 8,) said rocking-arm *l*² being loosely mounted or pivoted on the stud *j*², so as to move freely thereon. The pin *l*⁴ is pointed at one end and is supported on the rocking arm *l*² by the recessed projection *l*⁵, which is secured to said lever, the pin being normally pressed toward the pawl by a spring *l*⁶, which is arranged in the recess of the projection *l*⁵ and which surrounds said pin, the said pointed end of the pin being adapted to engage indentations in the pawl, so as to retain the tooth *l* in contact with the teeth of the ratchet-wheel *k* or the tooth *l*' in engagement with the teeth of the ratchet-wheel *k*', according to the position of said pawl. The rocking arm *l*² has an upwardly-extending arm *l*⁷, which is provided with a slot *l*⁸, adapted to be engaged by a bolt *m*, carried by the end of a link *m*', the latter connecting the rocking arm *l*² with the rock-lever *M*, through which the said rocking arm is moved on its pivot. This link has its end

radially adjustable in the slot *l*⁸ by simply turning the thumb-nut *m*², arranged on the end of the bolt *m*, and which serves to bind said bolt in the slot, so that different adjustments may be secured to vary the throw of the pawl and consequently the length of each movement of the clamp.

The rock-lever *M* is pivoted to the frame *H* and has a forked lower end which is passed through an elongated slot in the frame and the bed of the machine and spans a cam *n*, which is secured to a horizontal shaft *n*', said shaft being located beneath the bed *A* and journaled in brackets *n*² *n*³, depending from said bed. This shaft has a miter-gear *n*³ on one end thereof, which is in mesh with a like gear *n*⁴, secured to the vertical shaft *F*, by which the said horizontal shaft is rotated.

For automatically shifting the pawl *L* to change the direction of the feed, I provide a pair of standards *o* *o*', arranged on opposite sides of said pawl and carried by the rack-bar *h*. In these standards are arranged the thumb-screws *o*² *o*³, on which are the hand-lock nuts *o*⁴ *o*⁵, which hold the screws in a fixed position when once adjusted, the said screws having their inner ends in a path of a projection *o*⁶, which extends outwardly from the pawl *L*, so that as the standards travel back and forth with the rack-bar the ends of said screws will contact with the projection *o*⁶ and shift the position of the pawl, according to the direction of movement of the rack-bar. The rack-bar is prevented from moving too easily by a friction-brake which may consist of a curved spring *o*⁷, the ends of which contact with the upper surface of a portion of said bar. This brake is provided with a central boss *o*⁸, which is engaged by the end of a thumb-screw *o*⁹, which passes through a threaded aperture of the boss *o*¹⁰, so that the tension of the spring may be varied to secure the desired pressure on said rack-bar.

The top plate of the clamp *I* is preferably raised by the action of the cam-block *p*, which is secured to the end of a shaft or stud *p*', said shaft being journaled in a bracket or upright *p*², secured to and carried by the foot-plate *i* of the clamp. The cam is provided with two flat surfaces, so that by turning the handle *p*³, which is secured to one end of the shaft, the cam will be caused to lift the spring *i*³ of the top plate and retain the same in this position, owing to the pressure of said spring, which rests on the flat surface of the cam, being in an approximately vertical plane, as shown in Fig. 4. This movement of the top plate simultaneously operates on a tension-releasing lever *R*, which is pivoted to the head *C* of the overhanging arm. The lever *R* has its upper end wedge-shaped, so as to spread the tension-disks *r* *r* apart to release the thread and to prevent its breaking, the lower end of said lever being retained in contact with the top plate *i*² of the clamp by the

spring r' . This arrangement prevents the thread being broken while operating the clamp, and at the same time no separate movement is necessary to release said thread.

5 The operation of the machine will be readily understood from the foregoing description, in connection with the accompanying drawings. It will be seen, when the article is placed in the position shown in Fig. 5, that 10 by starting the machine a vertical and reciprocatory movement will be given the needle and needle-bar D at the same time rotary motion is imparted to the shaft n' , which, by means of the cam n , will rock the lever M on its pivot. This movement of the lever M gives movement to the rocking-arm l^2 , which carries the pawl L, causing the latter to give movement to the stud j^2 , by engaging the ratchet-wheels k k' . In the position shown, 15 the tooth l of the pawl engages the ratchet-wheel k , giving a step-by-step movement to the rack-bar toward the front of the machine by means of the segmental gear j , which is in mesh with the teeth of said rack-bar. The 20 rack-bar will continue to move in this direction until the end of the screw o^2 contacts with the projection o^6 of the pawl L, which will shift the latter on its pivot, so as to have the tooth l' engage the teeth of the ratchet-wheel k' , thereby causing the rack to move 25 in the opposite direction, so that the second row of stitches may cross those already made, the said pawl being yieldingly retained in either position by the spring-pressed pin l^4 . By this construction the row of stitches may 30 be caused to repeatedly cross each other, or the feed may be stopped or started in any desired position by the handle and segmental gear j .

35 It is not my intention to confine myself to the construction or arrangement shown, as this may be varied and other means may be employed for giving the step-by-step motion to the clamp; nor do I confine myself in the 40 application of my invention to any particular kind of machine, as the feed mechanism is independent of any particular shuttle or needle operating mechanism. The ratchet-wheels k and k' and the segmental gear may be dispensed with in some instances, and the double-acting pawl L made to engage directly with ratchet or other teeth arranged on the rack-bar. As shown in Figs. 9 to 11, Sheet 4, the 45 rack-bar has two series of teeth r and r' , located on opposite sides of the face of said rack-bar for the purpose of moving the same either forward or rearward, according to which series of teeth is engaged by the pawl, movement being imparted to said pawl in substantially 50 the same manner as heretofore described. The screws o^2 and o^3 contact with the projection o^6 for shifting the pawl to reverse the movement of the rack-bar; but in this case the 55 said projection is arranged below the pivot l^3 of the pawl, so that the same may be properly shifted by the adjustable screws carried by the standards o^4 , as heretofore explained.

The rock-lever M may be operated in some instances directly from the shuttle-driving mechanism and the additional counter-shaft n' thereby dispensed with. Other changes may be made, if found desirable, without departing from the spirit of my invention.

Having thus fully described my invention, what I claim as new, and desire to secure by Letters Patent of the United States, is—

1. In a sewing machine, the combination with suitable stitch-forming mechanism, of a clamp adapted to hold the article to be stitched; said clamp being arranged to move transversely of the machine toward either side thereof, and mechanism for imparting a step by step movement to said clamp, comprising a rack-bar for moving the clamp, a rocking arm, a double-acting pawl pivotally mounted upon said arm and adapted to impart motion to said rack-bar, and a driving shaft and intermediate mechanism for imparting movement to said pawl, together with means for positively shifting the pawl at a predetermined point in its movement in either direction, so as to reverse the direction of motion of said rack-bar and clamp, substantially as described.

2. In a sewing machine, the combination with suitable stitch-forming mechanism, of a rack-bar arranged to move transversely of the machine toward either side thereof, a clamp movable with said rack-bar and adapted to rigidly hold the article to be stitched, a rocking-arm, a double-acting pawl pivoted to said rocking-arm for giving a step by step movement to the rack-bar in either a forward or backward direction, a rock-lever pivoted to the frame and a link connecting said rock-lever and rocking-arm, together with mechanism for giving movement to said rock-lever and rocking-arm and devices for reversing the movement of the rack-bar as it reaches the limit of its movement in either a forward or backward direction, substantially as described.

3. In combination, a clamp, a rack-bar carrying said clamp and slidably held in a frame, a gear engaging the rack-bar and secured to a shaft journaled in the frame, ratchet wheels with oppositely arranged teeth rotating with said gear, a rocking-arm loosely mounted on said frame, a double-acting pawl pivoted to the rocking-arm and adapted to engage said ratchet wheels, and means for operating the rocking-arm, together with means for reversing the pawl and ratchet mechanism, substantially as described.

4. In a sewing machine, the combination with suitable stitch-forming mechanism, of a clamp adapted to bind and rigidly hold the article to be stitched, a rack-bar to which the clamp is secured slidably held in a frame, a gear secured to a shaft journaled in the frame and in mesh with the teeth of said rack-bar, ratchet wheels with oppositely arranged teeth secured to the shaft, a rocking-arm and a double-acting pawl pivoted to said rocking-arm, a rock-lever connected to the rocking-

arm, together with a cam and operating mechanism therefor for operating the rock-lever so as to give movement to said rack-bar, and means for shifting said pawl so as to reverse 5 the movement of the rack-bar, whereby a step-by-step motion either forward or backward may be given to the clamp, substantially as described.

5. In a sewing machine, the combination 10 with suitable stitch-forming mechanism, of a clamp adapted to bind and rigidly hold the article to be stitched, a rack-bar to which the clamp is secured, a rocking-arm, a double-acting pawl pivotally secured to the rocking- 15 arm for giving a step-by-step movement to said rack-bar, means for operating said rocking-arm, together with means carried by the rack-bar for automatically shifting the position of the pawl at a predetermined point in 20 its movement in either direction, whereby the direction of movement of the clamp may be changed, substantially as described.

6. In a sewing machine, the combination 25 with suitable stitch-forming mechanism, of a clamp adapted to bind and rigidly hold the article to be stitched, a rack-bar slidingly held in a frame to which the clamp is secured, a rocking-arm pivoted to the frame, mechanism for rocking said arm, a double-acting pawl piv- 30 oted to said rocking-arm so as to vibrate there- with and impart a step by step movement to said rack-bar, and means for yieldingly retaining said pawl in different positions on said rocking-arm, together with standards ar- 35 ranged on the rack-bar and having adjustable means adapted to contact with a portion of the pawl at predetermined points, whereby the direction of movement of the clamp may be automatically changed, substantially as de- 40 scribed.

7. In a sewing machine, a clamp comprising a top-plate and a foot-plate yieldingly connected together, the top-plate being provided with a depending tooth-edged rib and a slot

for the passage of the needle, and the foot-plate being provided with an angular lip adapted to project upwardly through the slot of the top-plate, whereby the article to be clamped may be rigidly held and properly aligned, substantially as described. 45 50

8. In a sewing machine, the combination with the frame and suitable stitch-forming mechanism, of a rack-bar arranged to slide forward and back on said frame, a clamp carried by the rack-bar and means for imparting a 55 forward and back step-by-step motion thereto, together with a spring friction brake ar- ranged to contact with a smooth surface of the rack-bar while the latter is moving in either direction, so as to steady the same and 60 prevent any uneven movement thereof and means for regulating the tension of said spring, substantially as described.

9. In a sewing machine, a clamp for holding the material to be stitched, consisting of 65 a foot-plate or cloth support having a sup- porting arm which extends to a movable clamp-carrying bar to which said arm is se- cured, a spring also secured at one end to 70 said bar arranged over and parallel with said arm but separated therefrom between the ex- tremities of the two parts and having a top- plate at its free end arranged above and yieldingly pressed into close proximity to 75 said foot-plate so as to bind and hold the ma- terial while the clamp is being moved by said clamp - carrying bar, and a cam rotatably mounted below said spring and between the same and said foot-plate supporting arm, and means for rotating said cam so as to raise and 80 hold the top-plate in an elevated position when desired, substantially as described. 8c

In testimony whereof I affix my signature in presence of two witnesses.

GEORGE H. COLLEY.
